CLAIM

The ornamental design for a measurement device, as shown and described.

DESCRIPTION

FIG. 1 is a front and right-side perspective view showing the measurement device;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The broken lines in FIGS. 1 through 7 illustrate portions of the measurement device that are not part of the claimed design. Appendix A includes computer-generated images that correspond to FIGS. 1-7.
